DISPLAY BOX FOR AN ELECTRIC SHAVER

Alfred W. Madl, Glendale, and David C. Anderson, Milwaukee, Wis., assignors to John Oster Manufacturing Co., Milwaukee, Wis., a corporation of Wisconsin

Filed Dec. 19, 1969, Ser. No. 20,578

Term of patent 14 years

Int. Cl. D9—04

U.S. Cl. D9—233

FIG. 1 is a perspective view of a display box for an electric shaver embodying our new design shown in the open position;

FIG. 2 is a perspective view thereof shown in the closed position;

FIG. 3 is a top plan view thereof in the open position;

FIG. 4 is a right side view thereof in the open position;

FIG. 5 is a sectional view taken along line 5—5 of FIG. 3;

FIG. 6 is a rear elevational view thereof in the open position; and

FIG. 7 is a left side view thereof in the closed position.

We claim:

The ornamental design for a display box for an electric shaver, as shown.
